MAGNETIC DRIVE FOR SHIPS

Henry A. Gentile, Barrington, R. I.

Application May 15, 1953, Serial No. 355,307

2 Claims. (Cl. 115—34)

This invention relates to an improved electrical propulsion system for boats.

A main object of the invention is to provide a novel and improved electrical propulsion system for boats, ships and the like, the system involving inexpensive components, being reliable in operation, and providing smooth control.

A further object of the invention is to provide an improved electrical propulsion system for a boat, said system eliminating the necessity for making openings in the hull of the boat for the propeller shaft, whereby the hull is rendered completely watertight, the system being easy to install, being efficient in operation, and reducing to a minimum losses such as those produced by turbulence or the like.

Further objects and advantages of the invention will become apparent from the following description and claims, and from the accompanying drawings, wherein:

Figure 1 is a horizontal cross sectional view taken through the hull of a boat constructed in accordance with the present invention and provided with an improved electrical propulsion system according thereto.

Figure 2 is a fragmentary side elevational view, partly in vertical cross section, of the hull of the boat shown in Figure 1.

Figure 3 is an enlarged vertical cross sectional view taken on the line 3—3 of Figure 2.

Figure 4 is an enlarged vertical cross sectional view taken on the line 4—4 of Figure 3.

Figure 5 is a horizontal cross sectional view taken on the line 5—5 of Figure 4.

Referring to the drawings, 11 generally designates a boat hull, said hull being formed of non-magnetic material, such as plastic sheet material, the hull being formed with the longitudinally extending, downwardly facing bottom channel 12 in which are located a plurality of propellers 13, the propellers being spaced longitudinally and also being laterally staggered along the channel 12.

Referring to Figure 3, it will be seen that each propeller 13 is mounted on a substantially longitudinally extending horizontal shaft 14 which is journaled in a housing 15 having an enlarged top portion 16 which is secured to the top wall 17 of the channel 12. As shown in Figures 3, 4 and 5, the annular enlarged housing portion 16 may be provided with a plurality of outwardly extending locking lugs 18 which are received in socket elements 19 integrally formed with the top wall 17 of channel 12, said socket elements 19 being arranged to receive the lugs 18 and the housing 15 being rotatable to lock the lugs 18 in the socket elements 19, a resilient deformable annular gasket 20 being interposed between the annular peripheral portion 21 of the housing member 16 and the surface of the wall 17.

Vertically journaled in the housing 15 is the worm shaft 22 provided with the worm 23 which meshes with the worm gear 24 secured on the associated propeller shaft 14. Secured to the top end of each worm shaft 22 is a rotor 25 of non-magnetic material on which is se-

2

cured the circularly arranged series of permanent magnets 26. The permanent magnets 26 are generally U-shaped and have their poles projecting upwardly, the poles being arranged in alternating polarity, as shown in Figure 5. The poles project closely adjacent to the bottom surface of the wall 17 of channel 12, as shown in Figures 4 and 5.

Mounted on the wall 17 are the respective electric motors 28, the motors being vertically arranged and being in alignment with the worm shafts 22. The shaft 29 of each motor has secured to its lower end a rotor 30 of non-magnetic material in which is mounted a series of circularly arranged electromagnets 31, the electromagnets 31 being arranged on a radius equal to the radius of the locus of the permanent magnets 26, whereby electromagnets 31 are in vertical alignment with the respective permanent magnets 26. Preferably, the same number of electromagnets 31 is provided as permanent magnets 26, and the cores of the electromagnets 31 are preferably of the same size and shape as the permanent magnets 26 and are arranged in opposing relationship to the permanent magnets, as shown in Figure 3. The pole faces of the electromagnets 31 terminate closely adjacent to the upper surface of the top wall 17 of channel 12, whereby the gap between the pole faces of the electromagnets 31 and the pole faces of the permanent magnets 26 is minimized. Since the wall 17 of channel 12 is relatively thin and since said wall is made of non-magnetic material, such as sheet plastic material or the like, the wall 17 introduces relatively small reluctance in the magnetic path between the electromagnets 31 and the permanent magnets 26, and thus substantial torque can be transmitted from the rotor 30 to the rotor 25 by means of the magnetic coupling between the electromagnets 31 and the permanent magnets 26.

As shown in Figure 4, the rotor 30 is provided with a peripheral flange 32 in which are mounted the slip rings 33 and 34, said slip rings being engaged by respective brush members 35 and 36 resiliently supported in a housing 37 mounted on the wall 17. Connected to the contact brushes 35 and 36 are the supply wires 37 and 38 which are connected by wires 39 and 40 to the main supply wires 41 and 42 connected to the electric motors 28. As shown in Figure 1, the wires 41 and 42 are connected by suitable conductors 43 and 44 to the respective stationary terminals of a double pole reversing switch 45 located in the control tower of the boat. One of the poles 46 of the switch 45 is connected through a control rheostat 47 to a generator wire 48 and the opposite switch pole 49 is connected to another generator wire 50. The generator wires 48 and 50 are connected through a master switch 51 to the output terminals of the generator 52, said generator being driven in a conventional manner, as by a turbine 53. Thus, when the switch 51 is closed, the motors 28 can be energized in parallel by closing the switch 45 in either a forward or reverse position, and the speed of the motors can be regulated by adjusting the control rheostat 47. Since the electromagnets 31 of each rotor 30 are connected in parallel with the associated electric motor 28, the electromagnets 31 are energized simultaneously with the electric motor and the current through the electromagnets 31 is regulated by the control rheostat 47. Therefore, the speed of the motors 28 is controlled simultaneously with the degree of current in the electromagnets 31 associated therewith, whereby the degree of magnetic coupling of the respective electromagnetic rotors 30 with their associated driven rotors 25 is regulated simultaneously with the regulation of the speed of the motors.

In operation, with the switches 51 and 45 closed, the motors 28 and the electromagnetic rotors 30 are simultaneously energized, whereby the motor torque is trans-

mitted to the driven rotors 25 through the magnetic field provided between electromagnets 31 and the permanent magnets 26, whereby the propeller shafts 14 are simultaneously driven and provide propulsion of the boat. The arrangement of the propellers 13 in the channel 12 provides effective longitudinal propulsion of the boat and reduces the turbulence resulting from the rotation of the propellers, since the channel 12 guides the water smoothly past the propellers. To reverse the direction of movement of the boat or to introduce a braking force to retard the speed of the boat, it is merely necessary to reverse the switch 45 and suitably adjust the rheostat 47 to provide the desired energization of the motors 23 and the electromagnetic rotors 30 associated therewith.

While a specific embodiment of an improved propulsion system for boats has been disclosed in the foregoing description, it will be understood that various modifications within the spirit of the invention may occur to those skilled in the art. Therefore, it is intended that no limitations be placed on the invention except as defined by the scope of the appended claims.

What is claimed is:

1. In combination with a boat having an imperforate bottom wall including an area of non-magnetizable material, a hollow housing having a closed lower end and an open upper end, means securing said upper housing end to the underside of said bottom wall, a horizontal propeller shaft journaled through said housing, a vertical shaft journaled in said housing, said vertical shaft having a lower end operatively connected to said propeller shaft and having an upper end, a first rotor fixed on the upper end of said vertical shaft, annular magnet means on said first rotor, said magnet means positioned adjacent said bottom, a motor mounted upon said bottom wall and rising therefrom, said motor having a vertical shaft having a lower end, a second rotor fixed on the lower end of said vertical motor shaft, and annular magnet means on said second rotor in axial alignment with the first mentioned magnet means and positioned adjacent to and above said bottom wall, said area of non-magnetizable

material corresponding to at least the juxtaposed areas of said annular magnet means, said securing means removably securing the housing to the bottom wall.

2. In combination with a boat having an imperforate bottom wall including an area of non-magnetizable material, a hollow housing having a closed lower end and an open upper end, means securing said upper housing end to the underside of said bottom wall, a horizontal propeller shaft journaled through said housing, a vertical shaft journaled in said housing, said vertical shaft having a lower end operatively connected to said propeller shaft and having an upper end, a first rotor fixed on the upper end of said vertical shaft, annular magnet means on said first rotor, said magnet means positioned adjacent said bottom, a motor mounted upon said bottom wall and rising therefrom, said motor having a vertical shaft having a lower end, a second rotor fixed on the lower end of said vertical motor shaft, and annular magnet means on said second rotor in axial alignment with the first mentioned magnet means and positioned adjacent to and above said bottom wall, said area of non-magnetizable material corresponding to at least the juxtaposed areas of said annular magnet means, one of said annular magnet means comprising a plurality of permanent magnets and the other annular magnet means comprising a plurality of electro-magnets, and energizing means connected to said electro-magnets.
